UNITED STATES PATENT OFFICE.

EDWARD W. STOLER, OF MANSFIELD, OHIO.

WIRE SPOKE.

Application filed April 17, 1923. Serial No. 632,680.

To all whom it may concern:

Be it known that EDWARD W. STOLER, a citizen of the United States of America, residing at Mansfield, in the county of Richland and State of Ohio, has invented certain new and useful Improvements in Wire Spokes, of which the following is a specification.

This invention relates to an improvement in spokes designed for use in wire wheels and the like, and is particularly directed to a method of forming the spoke to permit its yielding under load strains in a manner to avoid breakage.

The wire spoke of usual construction has a body or main length of uniform diameter throughout, and beyond such body is formed with somewhat enlarged terminal portions, one of which is headed and bent for cooperation with the hub of the wheel, and the other of which is threaded for adjustable connection with the usual rim nipple. In the use of the wheel, the spokes flex inwardly and outwardly under the recurring load strains and relief therefrom, and as the body portion or main length of the usual constructions is of uniform diameter throughout, the flexing tendency and strain is transferred to the terminal portions, the bend, or the threaded portion, or all such parts, with a resultant breakage at one or the other of these points.

The present method of construction consists in forming the body portion or main length of the spoke of reversely-tapered formation from or about the center of such main length toward the ends thereof, this construction providing a gradual decrease in diameter of the body portion from one end toward the central point, and a gradual increase from such minimum diameter toward the opposite end.

With this formation, the central point of the body length of the spoke is weaker than the terminal portions, so that under the flexing strain and relief the strain is directed toward such central point. As this central point is farthest from the points of resistance, that is, the connected terminals of the spoke, the result is a gradual and uniform curving of the spoke length under the flexing movement, with materially less liability of breakage.

The invention is illustrated in the accompanying drawings, in which:

Fig. 1 is sectional view of a wire wheel

showing the application of the spoke arrangement in a simple form, in order that the flexing strain may be understood.

Fig. 2 is an elevation of a conventional form of spoke, showing the line of bend or flexing when one end of such spoke is held and pressure is applied to the opposite end, to illustrate in a somewhat exaggerated manner the action of the spoke under working conditions.

Fig. 3 is a view of the improved spoke.

Fig. 4 is a view similar to Fig. 2, showing the results of a similar test on the improved spoke of this application.

The improved spoke 1 is as usual constructed of appropriate material, formed at the hub end with an enlargement 2, headed at 3, and bent adjacent the head, as at 4. Beyond the enlargement the spoke includes what may be termed the main length or body portion 5, the opposite terminal of the spoke being enlarged at 6, and threaded, as at 7.

In the usual type of spoke, indicated at 1', Fig. 2, the main length 5' is of uniform diameter, and under test, where one end of the spoke is held and pressure applied to the other end, to simulate actual use though in exaggerated form, the bending tendency 85 is at the juncture of the body length 5' with one or the other of the enlarged ends 2' and 6'. Thus a bending or flexing occurs in the instance illustrated, adjacent the enlarged end 2', as at 8'. This continued bending or flexing at this point, which occurs in the actual use of the spoke, soon results in a fracture of the spoke.

The improved spoke is shown in Fig. 3, and is distinguished from the conventional 95 formation in the particular method of constructing the body portion or main length 5. In the improved construction, this main length is of usual strength of material, but is of minimum diameter at or about the center of such length, as at 9, and of gradually increased diameter from such point 9 to the terminal enlargements. Thus the spoke is of weakest construction centrally of its main length or body portion, and under load strains, this central point being the weakest will yield first to the flexing of the spoke. As this yielding is at a point farthest from the application of pressure, the spoke will yield in a uniform and large 110 curve, as indicated at 10, Fig. 4. Thus no short bend strain is put on any portion of

the spoke, and the flexing may continue for a much longer period than with the preferred forms as previously constructed. The spoke of the improved form is thus of materially greater life than forms heretofore used.

It is to be particularly noted that the main length 5 of the spoke is quite sharply reduced in diameter immediately adjacent 10 the respective end enlargements 2 and 6, as clearly shown in Fig. 3, and that such main length is tapered toward its mid-length from each of these sharply reduced portions. This particular construction of spoke body, 15 including the sharply reduced portions adjacent the enlargements, is particularly important in lending to the spoke the desired resiliency at the central portion, for if the spoke was gradually tapered from the enlargements, instead of being sharply reduced as shown, the strain tendency would be all distributed at the point of narrowest dimension of the spoke and under such strain a liability of breakage at this narrowest 20 point might occur. With the sharply reduced portions adjacent the enlarged ones however, these particular points take care of some of the strain and sufficient of said strain is transmitted to the narrowest part 25 to absorb such strain and permit a resiliency of the central portion to avoid breakage.

The method of forming the spoke of the varying diameter may be mechanically carried out as preferred. However, it is believed that a simple and expeditious manner 30 of securing this result is by swaging through a hammering toward the center, that is a

series of hammers are arranged in radial lines on a chuck, with movements in and out toward the center, and by a constant hammering of about nine thousand blows to the minute, the swaging on a tapered form is carried out. This method of swaging is usual and needs no further explanation.

The improved spoke is therefore designed 40 for greater life than the usual spoke, by providing a weakened portion remote from the application of pressure, to insure a gradual and maximum curvature under flexing strains.

Attention is called to the fact that because of the rapid, extensive and intensive hammering of the metal to produce a spoke by the process herein described the same process will produce superior struts and bracing 50 wires for aeroplanes because the size and weight is reduced in tapering same, while at the same time the tensile strength thereof is increased and maintained because of the amalgamation of the fibers of the metal 55 produced by the intensive hammering process.

What is claimed as new, is:—

A wire spoke having enlarged terminals of substantially uniform diameter, and a 60 main body length intermediate the terminals, the body length being gradually tapered in both directions from said terminals, with the tapering portions meeting at substantially the mid-length of such body 65 length.

In testimony whereof I affix my signature.

EDWARD W. STOLER.
